INTERNATIONAL COMBUSTION ENGINEERING CORPORATION, A CORPORATION OF
DELAWARE

COKE COOLING APPARATUS

Application filed March 26, 1926, Serial No. 97,483, and in Germany May 21, 1925.

This invention relates to method of and apparatus for cooling coke and has particular reference to the efficient transfer and absorption of heat from the coke.

It has already frequently been proposed to cool the hot coke leaving the coke retorts by means of a current of gas passed through it. This idea very soon led to the heat of the cooling gases being industrially utilized and in particular to the hot gases being used for the heating of steam-generators.

In these first plants there was associated with each coke oven one cooling chamber, which, in turn, had a special steam-generator allotted to it. It is evident that such cooling apparatus involved a very costly plant and also very expensive working.

The further development of coke-cooling soon showed a tendency to separate the cooling plant from the coking plant and to simplify it, that is, to establish special cooling towers having as great a volume as that of a number of coke chambers. The cooling towers were designed for continuous working, that is to say, the charging of the tower and the discharging of the coke were effected substantially without interrupting the cooling process. Furthermore, the conveyance of the cooling gas was improved by keeping the entire quantity of gas shut off from the outer air and continuously in circulation, constantly taking up heat in the coke tower and delivering heat to the steam-generator.

Just as numerous as the improvements in the cooling plant are the improved measures in connection with the method of arranging the steam-generators connected with the cooling tower. After originally complete separation of cooling tower and steam boiler, the tendency very soon became noticeable to associate the two in a single structural block. This tendency led to surrounding the cooling tower with a water jacket intended to take up the heat of the coke directly. This last-mentioned method of construction, however, did not lead to the desired result, as it was not possible in such a steam boiler, constructed as a hollow jacket, to control the customary steam pressures and steam superheats. Cooling tower and boiler were, therefore, sep-

arated again, thus abandoning direct transmission of heat, and fire-tube boilers of known kind were employed as heat-absorbers, to which the circulating cooling gases give up their heat. This last-mentioned system is 55 certainly to be regarded as the latest stage of the development in the cooling of coke up to the present. As has been stated, however, this construction involves giving up advantages of an economical nature, for both the 60 direct transmission of heat and also the most compact construction possible of cooling chamber and steam-generator were abandoned.

The present invention consists essentially 65 in the construction of coke-cooling apparatus in which the advantages of direct transmission of the heat are made available in an industrially practicable and particularly advantageous manner. According to 70 the invention the cooling chamber is bounded as far as possible on all sides by heat-absorbing boiler surfaces, which are composed of tubes. For this purpose so-called finned tubes (tubes with lateral fins or 75 vanes) are preferably employed, the fins of adjacent tubes overlapping one another and forming a fluid-tight and rigid metal wall, which takes up a large part of the heat of the coke directly as radiant heat. The rest 80 of the boiler heating surface is located in water-chamber elements or steep-tube elements arranged behind the finned tubes and preferably forming with the row of finned 85 tubes a unitary boiler aggregate.

The portion of the heat of the coke passing to the boiler by direct contact and radiation, which is found by experience to need substantially less heat-transferring area than is the case with the transmission of heat by 90 means of a gaseous medium, is increased according to the invention by imparting to the cooling vessel an elongated rectangular form, so that the wall surface has the greatest practicable area in relation to the volume. By this increasing of the radiating coke surface and of the cooling action, the cooling 95 time is considerably shortened, and, consequently, the quantitative capacity of the plant substantially increased.

According to the invention the wall tubes are only provided with lateral fins or covered on the rear side up to the height of the layer of coke, so that the hot gases can pass transversely between the tubes above the column of coke for the purpose of heating the superheater and the parts of the boiler located behind it. As already stated, the steam-generator is constructed as a water-tube boiler with headers or as a steep-tube boiler, and is united with a cooling chamber to form a unitary structural block. The advantages of this compact construction as regards economizing heat consist in the direct absorption of heat by the inner water-tube wall, and, furthermore, in the fact that only comparatively cold parts of the boiler block are in contact with the outer air, and, therefore, a comparatively cheap insulation is sufficient to limit the loss by thermal radiation to the lowest practicable amount. As compared with the constructions hitherto known, the invention is particularly distinguished by the fact that for the boiler and the cooling chamber, a single insulation is sufficient, that the gas passages connecting the boiler with the chamber are omitted, that the weight of the structural block is considerably smaller than when boiler and chamber are separated, and that in consequence of the reduction in weight and of the diminution in the space required, the structural supporting of the cooling chamber and the boiler is considerably simplified and cheapened.

The subject matter of the invention is illustrated by way of example in the accompanying drawings, wherein:

Fig. 1 shows a cross-section through a cooling plant according to the invention.

Fig. 1a is a horizontal section taken on the line 1a—1a of Fig. 1 with the parts appearing below the plane of the section omitted.

Fig. 2 shows a cross-section through a row of finned tubes on the line 2—2 of Fig. 1.

Fig. 3 shows a modified constructional form of the invention.

Fig. 4 shows a section on the line 4—4 of Fig. 3.

Fig. 5 shows a cross-section through another constructional form of the tube wall, and

Fig. 6 a partial section through a further constructional form of the invention.

Fig. 1 shows a downwardly expanding cooling chamber 1, which is closed at the top by a covering hood 2 and at the bottom by a discharge conveyor 3. The covering hood 2 is opened in a known manner before the charging of the chamber 1 by a lifter on the coke-supplying apparatus, (not shown) and is automatically closed after the charging by the action of a counter-weight (not shown).

The chamber 1 is laterally bounded by walls consisting of tubes 4. The wall tubes 4

are provided up to about the height of the coke filling with laterally overlapping fins 6 (see Fig. 2), while above the coke filling these lateral fins are omitted. The tubes 4 are rolled at the bottom into boiler drums 7 and open at the top into collecting chambers or headers 8, which communicate with a further upper drum 9 (connection not shown). The lower drums 7 are connected with the drums 9 by steep tubes 10, which are subdivided by flue-separating walls 11 into a plurality of nests or bundles. Between the tube walls and the steep tubes 10 are arranged superheaters 12.

Instead of the steep-tube boilers, water-tube elements may, of course, be fitted in, and, similarly, it also lies within the scope of the invention to jacket the front or end walls of the cooling chamber, as well as the side walls, with steam-generator tubes traversed by water.

The supplying of cooling gas is effected in a known manner from below by means of the strainer 13, which is connected by pipes 14 with one or more fans 15, the suction pipe 16 of which opens into the last boiler flue.

For the introduction of the hot coke there is arranged in the upper part of the chamber a filling hopper 16, which projects so far into the chamber 1 that the material, heaping it self up at the natural angle of repose, does not rise above the height of the tube wall which is closed at the back, so that no pieces of coke can fall through the interstices between the tubes into the boiler flues.

Underneath the filling hopper are provided at suitable distances breaking beams 17 which split and disintegrate the coke cakes introduced.

The cooling tower is united with the boiler into a unitary comparatively narrow structural block which, on all sides, is shut off and insulated from the outer air. As Fig. 1 shows, notwithstanding the compact construction, the accessibility of the cooling chamber and of the boiler is quite well guaranteed, the possibility of superintending the plant ensured, and the removal of flue dust rendered possible in a simple manner. According to the invention the fire-proof lining is limited to the region of the high temperatures and consists of blocks 28 which, in a manner known in itself, are locked on to rolled girders 29.

Fig. 3 shows a section through a modified constructional form of the cooling plant, wherein the boiler is arranged only on one side of the cooling chamber. This constructional form is particularly suitable for a cooling plant which has only a small quantity of coke passing through it and in which a comparatively small boiler heating surface suffices to take up the heat. The side walls of the cooling chambers are here formed of simple water tubes 18 (compare Fig. 4).

located close to one another, of which every second tube is bent outwards above the coke filling and leads into a special water chamber 30. The fluid tightness of the chamber wall may, if desired, be enhanced by covering the tubes on the rear side. Fig. 5 shows a second constructional form of the chamber wall, which, according to this figure, consists of simple water tubes 19, the spaces between which are covered by filling pieces 20. In order to obviate a one-sided gas outlet in the constructional form illustrated in Fig. 3, with consequent non-uniform cooling, a part of the cooling gases are collected on the side of the cooling chamber opposite to the boiler in a longitudinal passage 21 and are led through by-pass flues 22 to the boiler side, where the by-pass flues open into a longitudinal chamber 23, which is provided throughout its length with gas outlet apertures 24. The longitudinal chamber may be so arranged that the by-passed quantity of heating gas traverses the superheater, or, as is the case according to Fig. 3, is passed directly into the boiler flues. The water chambers of the wall tubes on the side remote from the boiler preferably communicate with those on the boiler side, so that in all the water tubes a unitary circulation of water takes place.

As the individual constructional examples show, the wall tubes 4, 18, 19 are not extended right to the discharge end of the cooling chamber. They preferably only extend so far downwards as to ensure a sufficiently direct heat-absorption. Obviously, it also lies entirely within the scope of the invention to carry the tube walls right through to the discharge end of the cooling chamber.

In order that the column of coke in its descent may not meet with any great resistance, it is preferable to smooth the transition of the side walls from the metal wall to the masonry wall. According to the invention, this is rendered possible by the wall tubes carrying, at their lower ends, protecting flanges 25 diverging conically upwards, with which they rest upon the masonry 26. In this manner disturbing projections in the side walls are conveniently obviated.

Fig. 6 shows a specially advantageous superheater arrangement above the lateral tube wall 5. The wall tubes are here covered throughout their length. The hot cooling gases pass through the superheater 12 into the rear boiler flues. The special advantage of this construction consists in the fact that the covering of the cooling chamber admits of being replaced in the range of the high temperatures by a simple and inexpensive plate covering 27.

I claim:—

1. Apparatus for cooling coke which comprises a cooling chamber having an inlet at the top and an outlet at the bottom, a plu-

rality of water tube boilers at the sides of said chamber each including spaced banks of spaced boiler tubes, and baffles associated with said banks so as to provide a plurality of gas passes for the up and down flow of gases through the boiler; and means for circulating a cooling medium through the chamber and the passes of the boilers in a continuous circuit, said means including a strainer having an opening for the introduction of the cooling medium substantially in the center of the chamber.

2. Coke cooling apparatus comprising an outer shell, a cooling chamber in said shell the lateral walls of which are substantially defined by water tubes diverging downwardly, a coke inlet at the top of the cooling chamber and a coke outlet at the bottom of said cooling chamber.

3. Coke cooling apparatus comprising water tube boiler means including boiler tubes defining lateral walls of a cooling chamber, spaced banks of spaced boiler tubes, and baffles associated with said banks so as to provide a plurality of gas passes for the up and down flow of gases through the boiler, means for admitting coke into said cooling chamber, means for admitting cooling gas into said cooling chamber, and a gas outlet for said cooling chamber through which gases may pass to the boiler passes.

4. Coke cooling apparatus comprising water tube boiler means including boiler tubes defining lateral walls of a cooling chamber spaced banks of spaced boiler tubes, and baffles associated with said banks so as to provide a plurality of gas passes for the up and down flow of gases through the boiler, means for admitting coke into said cooling chamber, means for admitting cooling gas into said cooling chamber, a shell surrounding said boiler means and cooling chamber, a gas outlet for said cooling chamber through which gases may leave said chamber and pass to the said gas passes, and means for leading gases from said gas passes into said cooling chamber.

5. Coke cooling apparatus comprising water tube boiler means including boiler tubes defining lateral walls of a cooling chamber, spaced banks of spaced boiler tubes, and baffles associated with said banks so as to provide a plurality of gas passes for the up and down flow of gases through the boiler, means for admitting coke into said cooling chamber, a gas outlet for said cooling chamber through which gases may pass to said gas passes, and means for leading gas from said gas passes into said cooling chamber.

6. Coke cooling apparatus comprising water tube boiler means including boiler tubes defining lateral walls of a cooling chamber, spaced banks of spaced boiler tubes, and baffles associated with said banks so as to provide a plurality of gas passes for the up

and down flow of gases through the boiler, means for admitting coke into said cooling chamber, a gas outlet for said cooling chamber through which gases may pass to said gas passes, and means for leading gas from said gas passes into said cooling chamber, together with a refractory enclosure for said boiler means and cooling chamber.

7. Apparatus for cooling coke comprising an outer shell, boiler means in said shell including water tubes spaced from said outer shell defining lateral walls of a cooling chamber and spaced banks of water tubes each comprising a plurality of spaced water tubes located in the space between said first mentioned water tubes and said shell, a gas outlet for said cooling chamber, means for introducing coke into said chamber, and means for circulating a gaseous medium through said cooling chamber and over said banks of water tubes.

8. Apparatus for cooling coke comprising an outer shell, boiler means in said shell including water tubes spaced from said outer shell defining lateral walls of a cooling chamber and spaced banks of water tubes each comprising a plurality of spaced water tubes located in the space between said first mentioned water tubes and said shell, a gas outlet for said cooling chamber, means for introducing coke into said chamber, and means for circulating a gaseous medium through said cooling chamber and over said banks of water tubes, together with superheater elements located in the aforesaid space, and means for leading steam from the boiler means to the superheater elements.

9. Coke cooling apparatus comprising boiler means including water tubes defining lateral walls of a cooling chamber, spaced banks of spaced boiler tubes, and baffles associated with said banks so as to provide a plurality of gas passes for the up and down flow of gases through the boiler; the water tubes defining opposite walls of said cooling chamber being upwardly inclined toward each other, means for admitting coke into said chamber, and means for admitting cooling gas into said chamber.

10. Coke cooling apparatus comprising boiler means including upright water tubes defining lateral walls of a cooling chamber, spaced banks of spaced boiler tubes, and baffles associated with said banks so as to provide a plurality of gas passes for the up and down flow of gases through the boiler, the tubes defining opposite walls of said cooling chamber being upwardly inclined toward each other, means for admitting coke into said chamber, and means for admitting cooling gas into said chamber, the tubes defining lateral walls for the cooling chamber being provided with fins terminating short of the upper ends of the tubes to permit gas to pass from said cooling chamber to said gas passes.

11. In apparatus for cooling coke, upright water tubes substantially defining lateral walls of a cooling chamber, said tubes being spaced apart, and fins on said tubes terminating short of the upper ends of the tubes and closing the space between the tubes for a substantial portion of the length of the tubes.

In testimony whereof I have hereunto signed my name.

CARL SCHWARTZ.
